AQUATIC AMUSEMENT DEVICE

Hyla F. Maynes, North Tonawanda, N. Y., assignor of one-half to Emma C. Maynes, North Tonawanda, N. Y.

Application March 16, 1936, Serial No. 69,185

7 Claims. (Cl. 114—57)

This invention relates to aquatic amusement devices and it has particular relation to a motor boat adapted to be navigated in pools, lakes, tanks, etc., in amusement parks, or the like, for the enjoyment of children and adults.

One object of the invention is to provide a motor driven boat constructed so as to be safe against capsizing, but adapted to be steered harmlessly against, and shuffled among, other similar boats.

Another object of the invention is to provide an improved hull construction for motor boats of the type employed for amusement, whereby the propeller and boat hull are protected against injury in the event of collision.

Another object of the invention is to provide a type of amusement boat including a novel seating arrangement for a plurality of passengers, as well as protective structure surrounding the passengers to shield them from splashing of water or danger of being struck incidental to collision of boats.

The boat is simple in construction, of sheet metal, or other durable material, and includes a relatively plain hull of substantially oval shape in plan and sloping gently from the zone of the water line upwardly to a central turret-like structure in which passengers are adapted to be seated and in which a small motor is installed. The hull also slopes downwardly and inwardly from the water line, and a central channel formed centrally of the hull bottom tapers from the front toward the rear of the boat to provide a partially surrounding structure for the propeller which is disposed toward the front of the boat. The channel provides for proper application of the propeller to the water in that an adequate body of water surrounds the propeller even though the boat may be in water only sufficiently deep to float it.

The seats are so arranged on the bottom of the boat immediately above the sloping channel that one passenger can be seated upon a rear seat with his knees on opposite sides of the front seat.

In the drawing:

Fig. 1 is a plan of motor boat constructed according to the invention;

Fig. 2 is a side elevation of the motor boat;

Fig. 3 is a diagrammatic section taken substantially along the line III—III of Fig. 2, and

Fig. 4 is a fragmentary vertical section, on a larger scale, taken substantially along the line IV—IV of Fig. 1.

Referring to Fig. 1 of the drawing it will be observed that the plan contour of a boat 10 shown

therein is substantially oval, although it is to be understood that the contour is not necessarily of this particular configuration. It has been found that, in order to minimize possibility of capsizing, the boat is so designed that its length is less than twice its width, and its main body portion is relatively flat.

A main hull 12 of the boat includes a lower section 14 and an upper section 15 which are somewhat dish-like in form and are applied to each other in opposed relation. A horizontal peripheral corner 16 is thus formed surrounding the hull at its extreme outer edge and the lower surface of the lower section 14, as well as the upper surface of the upper section 15, is convex. 15 These hull surfaces converge toward each other at a relatively sharp angle at all locations around the outer marginal portions of the hull. A water tight gasket 17 is inserted between the hull sections adjacent their outer edges and suitable fastening elements 18 secure these marginal portions in tightly clamped relation upon the gasket.

The upper hull wall or section 15 can be formed in sections and secured together, as indicated at 19, by means of bolts, or other suitable 25 connecting means.

Reinforcing ribs 20 extending transversely or substantially radially inside and toward the marginal portions of the hull have relatively wide outer base portions 22 and inwardly extending 30 arms 23 tapering and conforming generally to the contour of the inner surfaces of the hull sections which they engage and brace. These ribs can be overlapped or otherwise associated so as to be firmly secured together and to the hull sections in any suitable manner, for example, by welding, bolting, riveting, or the like.

A bottom channel 25 formed in the lower portion of the lower section has its deeper portion 26 extending uniformly in size approximately one 40 third the distance from the bow of the hull to the stern, and then tapers from a location, indicated approximately at 27, to become shallower toward the boat stern, but not necessarily narrower. While the tapering of the channel commences approximately one third of the distance from the bow to the stern of the boat in the example of the construction shown in the drawing, the invention is not dependent upon this precise relation, but it is preferable that the tapering 50 begin at least nearer the bow, and that such tapering terminate by merging into the configuration of the bottom surface of the lower section 14 at a location nearer the stern of the boat.

- A turret 30 of substantially the same general plan configuration as the hull is built rigidly in the central portion of the latter and extends a considerable distance above the main hull body. 5 The circumferential wall of the turret is located a considerable distance inwardly from the edge of the hull at all points of the latter. In fact, the turret is approximately one half the width of the hull and also about one half the length thereof. 10 Also, the hull body exclusive of the turret is relatively flat and its depth is much less than half the maximum width of the hull.

The floor of the turret is defined by the bottom of the lower section 14 and a front seat 32 is installed in the central portion of the turret as viewed from above. This seat slopes rearwardly along the central floor portion defining the tapering channel. A second seat 33 of somewhat crescent or arcuate shape is disposed immediately 20 behind the front seat and in contact therewith, or as a part thereof. Spaces 37, similar to troughs, on opposite sides of the front seat are provided for receiving the feet of the passenger carried by the rear seat, and these spaces also extend forwardly a sufficient distance to accommodate the feet of the passenger carried by the front seat.

Two passengers can thus be seated in a relatively small space and the feet of the rear passenger can extend forwardly as far forward as, or 30 farther than, the knees of the front passenger. Both seats 32 and 33 slope rearwardly according to the taper of the floor defining the channel 28 in the lower portion of the hull. Since the passenger seats are approximately in the bottom of 35 the boat, the center of gravity of the boat when loaded with passengers is so low as to be an important factor in avoiding any tendency of the boat to capsize during its operation. If desirable, a suitable padding or upholstering 38 can 40 be provided about the inside wall of the turret adjacent the seats.

It is apparent that the two seats can be made in the form of a single seat structure and, as indicated in Fig. 2, the rear seat can be arranged 45 at a slightly greater elevation than the front seat. The shoulder 40 at the junction of the seats conforms to the contour of the rear portion of the front seat and constitutes a modified back to prevent the front passenger from sliding rearwardly.

The motive power of the boat is supplied by a conventional small motor 42, for example, like the well-known outboard motor, or even the electric motor, and is supported in a bearing support 43 55 rigidly carried in the front portion of the hull floor in the area of the front of the turret. A drive shaft 45 for the motor is disposed in a substantially vertical tubular housing 46 which is rotatably mounted in the bearing support 43 and 60 carries the motor thereon. A collar 47 rigidly embracing the housing rests upon the upper side of the bearing support 43 to serve as a thrust bearing in carrying the weight of the motor.

A propeller 50 which is mounted upon the 65 lower end of the housing 46 is connected to the shaft 45 by conventional gearing 52, and is located in the deeper portion of the channel 28 adjacent the front extremity of the turret.

This type of motor is provided with a steering 70 wheel or handle 53 for turning the entire housing 46 and motor assembly in the bearing support 43 incidental to the steering of the boat, and a rudder 54 is provided upon the lower portion of the rotatable housing 46 opposite the rudder.

75 It is intended that the peripheral corner of the

hull structure be substantially even with the water line when the motor boat is operated. Then in maneuvering several boats against one another in a body of water, the sloping surface of one of the hulls will ride up the sloping upper surface of another boat hull. Thus sudden shocks which might injure the boats are avoided. Likewise, since the outer circumferential surface of the turret is concave and merges into the curvature of the hull, the edge of a colliding boat hull will slide over this surface in the event force at impact is sufficient to move the boat edge to the location of the turret.

It will be apparent that boats of the kind described are well adapted to withstand buffeting 15 and shuffling among one another without injury either to the boat structure or to the passengers carried thereby. On the other hand, the variety and interest afforded in navigating the boats assures amusement attractive to both children and 20 adults.

Although only one form of the invention has been shown and described in detail, it will be apparent to those skilled in the art that the invention is not so limited, but that various changes 25 can be made therein without departing from the spirit of the invention or from the scope of the appended claims.

I claim:

1. An amusement device comprising a boat 30 hull body for navigation in water and having a length not exceeding twice its width, upper and lower hull walls of the body including outer surfaces for engaging and tilting a like hull and converging toward each other to their outer periphery to form a circumferential corner, said corner substantially defining the water line of the hull body while afloat, whereby other amusement devices of similar construction are slidable over the converging surfaces in response to navigating the 40 boats against each other.

2. An amusement boat having a length not exceeding twice its width and comprising a relatively flat hull body, upper and lower walls of said body including outer surfaces for engaging and tilting a like hull and converging outwardly 45 to form circumferential corners coinciding substantially with the water line of the body, seating structure arranged centrally of the hull body at a location materially spaced in horizontal directions from the entire circumferential corner.

3. An amusement having a length not exceeding twice its width and boat comprising a relatively flat hull body, upper and lower walls of said body including outer surfaces for engaging and tilting a like hull and converging outwardly to form circumferential corners coinciding substantially with the water line of the body, seating structure arranged centrally of the hull, and a turret incorporated in the hull body and having a circumferential upright wall to shield a passenger carried upon the seating structure, the base of the turret being materially spaced in horizontal directions from the entire circumferential corner.

4. An amusement boat having a length not exceeding twice its width and comprising a relatively flat hull body, upper and lower walls of said body including outer surfaces for engaging and tilting a like hull and converging outwardly to form circumferential corners substantially defining the water line of the body while afloat, a seat arranged centrally of the hull, a turret extending upwardly from the hull body and having an upright protecting wall enclosing the seat, the base 70 75

of the turret being spaced materially in horizontal directions from the entire circumferential corner, and a motor mounted in front of the seat and having combined rotatable driving and steering means extending through the boat bottom.

5. An amusement boat having a length not exceeding twice its width and comprising a relatively flat hull body, upper and lower walls of said body including outer surfaces for engaging and 10 tilting a like hull and converging outwardly to form circumferential corners coinciding substantially with the normal water line of the boat, seating structure mounted centrally of the hull body at a location materially spaced in horizontal 15 directions from the entire circumferential corner, the bottom of the hull having a channel tapering rearwardly from a location nearer the boat bow, and a driving and steering motor mounted in front of the seating structure and having a 20 propeller disposed in the deeper portion of said channel.

6. An amusement boat having a length not exceeding twice its width and comprising a relatively flat hull body, upper and lower walls of said body including outer surfaces for engaging and 25

tilting a like hull and converging outwardly to form circumferential corners substantially coinciding with the normal water line of the boat, and a turret extending upwardly from the hull and having an upright wall spaced materially in horizontal directions from the entire circumferential corner, the outer surface of the turret being concave and merging into the contour of the hull body.

7. An amusement boat having a length not exceeding twice its width and comprising a relatively flat hull body, upper and lower walls of said body including outer surfaces for engaging and 10 tilting a like hull and converging outwardly to form circumferential corners at substantially the normal water line of the boat, a double seat arranged centrally of the hull body at a location materially spaced in horizontal directions from the entire circumferential corner, said double seat including a front seat and a wider rear seat partially embracing the front seat whereby a passenger seated upon the rear seat will have leg 15 space on opposite sides of the front seat.
